UNITED STATES PATENT OFFICE.

JOHN C. SCHILKE, OF MILWAUKEE, WISCONSIN.

GAME.

Application filed April 14, 1926. Serial No. 101,845.

This invention relates in general to improvements in amusement devices, and relates more specifically to an improved game especially adapted for use by children.

5 An object of the invention is to provide a new, useful and relatively inexpensive game which is not only extremely amusing, but which is also highly educational.

A clear conception of an embodiment of 10 the present invention, and of the mode of playing a game constructed in accordance therewith, may be had by referring to the drawing accompanying and forming a part of this specification in which like reference 15 characters designate the same or similar parts in the various views.

Fig. 1 is a top view of the improved game, showing one side of the reversible runway, and having a fragment of a cover applied 20 to the enclosing box.

Fig. 2 is a top view of the game, showing the opposite side of the reversible runway.

Fig. 3 is a longitudinal vertical section through the game, the section being taken 25 along the line III—III of Fig. 1.

Fig. 4 is a transverse vertical section through the game, the section being taken along the line IV—IV of Fig. 1.

Fig. 5 is an enlarged central longitudinal 30 section through one of the tumbling objects or capsules of the game.

The new and improved game comprises in general a box 30; an inclined runway 31 reversibly disposed within the box 30 and 35 having a plurality of circular perforations or openings 32 near the lower end thereof; and one or more specially devised tumbling objects or capsules 33 formed to travel end over end down the runway 31 and to enter 40 any of the openings 32. The box 30 may be constructed of wood or cardboard and is preferably provided with a suitable cover 34 upon which the instructions for playing the game may be printed or otherwise applied. The runway 31 may likewise be formed of wood or stiff cardboard and is 45 preferably surfaced with velvet finish paper or cloth in order to eliminate excessive slippage of the objects 33 while travelling therealong. The supporting blocks 35 secured within the corners of the box 30 serve to 50 sustain the runway in properly inclined position, and the latter merely rests by gravity upon the blocks 35 thereby permitting ready 55 reversal of the runway 31. The upper portion of the runway 31 may be provided with

goal lines 36 and the perforations or openings 32 are suitably numbered on opposite sides of the runway 31 as shown in Figs. 1 and 2 respectively, for purposes to be more 60 fully explained hereinafter. Each of the tumbling objects or capsules 33 comprises a two-part elongated circular shell 37 forming a housing for a metal ball 38 which is freely rollable from end to end within the shell. 65 The opposite ends 39, 40 of the shell 37 are distinctively marked as by different colors, the end 39 for example being colored red and the opposite end 40 being white.

When manipulating the improved game, 70 each of a number of players may assume a turn at releasing one of the objects 33 from the goal line 36 and permitting the released object to tumble end over end down the inclined runway 31 toward the receiving openings 32. If the object upon reaching the lower end of the incline, fails to enter any of the openings 32, no score is counted. If the object 33 lands with its white end up in one of the openings 32, then the player 75 adds to his score the value of the receiving opening. If however the object 33 lands with its red end up in one of the openings 32, then the player deducts from his score the value of the receiving opening. The 80 winner of the game may be determined either by the highest number of good points after a definite number of trials by each player, or by being the first to attain a definite total number of good points. The 85 game may obviously be played by any number of individuals, and any desired number of objects or capsules 33 may be provided.

When the game is being played by children or others who are beginners in the 90 study of addition and subtraction, it is preferable to utilize the low numbered side of the runway 31, as shown in Fig. 1. As the 95 players become better versed in addition and subtraction, the runway may be readily reversed and the higher numbered openings 32 shown on Fig. 2, may be utilized. While the 100 designating numbers used in the specific embodiment illustrated, have been selected at random, it will be apparent that any desired scheme of numbering may be employed. By providing tumbling objects 33 having distinctively marked opposite ends, the exposure of either of which designates either an addition or a subtraction of points, 110 the players are compelled to exercise their arithmetical ability, thus making the game

highly educational without detracting from its value as an amusement device. The peculiar movement of the tumbling objects 33 gives action to the game and provides a fascination which is sure to appeal to adults as well as to children.

The improved game is obviously relatively inexpensive as the objects 33 may be produced from ordinary ball bearings and capsules 37 such as are commonly employed for medicinal purposes, while the box 30, runway 31 and the cover 34 may be made of wood or paper, or even of sheet metal. The entire device is extremely simple and compact and no high degree of intelligence is required in its manipulation.

It should be understood that it is not desired to limit the invention to the exact details of construction and to the precise mode of operation herein shown and described, for various modifications within the scope of the appended claims may occur to persons skilled in the art.

It is claimed and desired to secure by Letters Patent:

1. In a game, an inclined runway having an opening near its lower end, and an elongated object formed to tumble end over end along said runway and to set upright upon entering said opening, said object having its opposite ends distinctively marked and only one of said ends being visible when said object rests within said opening.

2. In a game, an inclined runway having an opening near its lower end, and an object comprising an elongated shell having a ball

therein for tumbling said shell end over end along said runway and for causing said shell to set upright upon entering said opening, said shell having its opposite ends distinctively marked and only one of said ends being visible when said shell rests within said opening.

3. In a game, an inclined runway having a plurality of openings near its lower end, and an elongated object formed to tumble end over end along said runway and to set upright upon entering an opening, said object having its opposite ends distinctively colored and only one of said ends being visible when said object rests within an opening.

4. In a game, an inclined runway having a plurality of circular openings near its lower end, and an object comprising an elongated circular shell having a ball therein for tumbling said shell end over end along said runway and for causing said shell to set upright upon entering an opening, said shell having its opposite ends distinctively colored and only one of said ends being visible when said object rests within an opening.

5. In a game, a box, an inclined perforated runway reversibly disposed within said box, and an elongated object having distinctively colored opposite ends and formed to tumble end over end along said runway and to set upright upon the bottom of said box after entering a perforation of said runway.

In testimony whereof, the signature of the inventor is affixed hereto.

JOHN C. SCHILKE.
